UNITED STATES PATENT OFFICE.

WALTER H. WHITTIER, OF GRAND RAPIDS, MICHIGAN, ASSIGNOR, BY MESNE ASSIGNMENTS, TO KELVINATOR CORPORATION, OF DETROIT, MICHIGAN, A CORPORATION OF MICHIGAN.

REFRIGERATOR.

Application filed July 26, 1926. Serial No. 124,866.

This invention relates to refrigerators, and more particularly to supporting devices for anchoring brine tanks within the cooling chambers.

Many refrigerators are constructed without provision being made for securing a brine tank carrier. When no provision is made for anchoring the brine tank carrier, considerable difficulty is encountered, because the installation must be made interiorly of the cooling chamber, the carrier must be secured to support a considerable weight, and when the anchoring devices are extended through the cooling chamber lining care must be taken to prevent the passage of air through openings formed to receive the anchors. Under such circumstances, considerable time is therefore required to install a brine tank carrier, and generally, at best, such installations are makeshift structures.

An object of my invention is to overcome the above difficulties by providing a refrigerator during its assembly with permanent anchors, to which the carrier of a brine tank can be secured, such anchors being designed to utilize a minimum space within the cooling chamber, so that such space is not restricted when the use of ice is desired.

A further object of my invention is to provide a refrigerator with anchoring devices to which a brine tank carrier can be quickly attached when it is desired to utilize a mechanical cooling apparatus.

These and other objects of the invention will appear more fully in the following description and will be set forth in the appended claims.

In the accompanying drawings, Fig. 1 is a front elevation of a refrigerator with a door opened and showing my invention installed in a cooling chamber; Fig. 2 is a vertical sectional view illustrating one of the anchoring devices attached to the refrigerator; and Fig. 3 is a similar vertical sectional view of a modified form of anchoring device.

Referring now to the drawings by characters of reference, 10 illustrates a refrigerator of conventional design, having a door 11 which closes the cooling chamber, and doors 12 and 13 which close food storing chambers. The inner top wall of the refrigerator casing comprises a layer of heat insulating material, such as cork, sections of

which are spaced by means of wooden supporting strips 14, and the lining 15 within the casing forms the cooling chamber within which either ice or a brine tank can be used, the brine tank, it will be understood, encloses an evaporator of a mechanical cooling apparatus.

Anchoring devices, for the attachment of the brine tank preferably metal straps 16, are permanently secured to the supporting strips of the inner top wall of the refrigerator casing and extend interiorly of the lining 15. In the preferred form of one of such anchoring devices, I utilize an anchoring element in the form of a bolt having a threaded shank 17, which is inserted through aligned openings 18 and 19 formed respectively in the top of the lining 15 and the supporting members 14 of the refrigerator casing. Securing means are provided to fasten the anchor element and consist of a washer 20 and a nut 21, which are inserted on the threaded end of the shank 17 which projects through the casing wall. The nut is screwed upon the shank 17 to draw the head 22 of the bolt tightly against the interior face of the lining 15. It will be understood that a plurality of such anchoring devices are utilized to provide a suitable support for the tank carrier, and that such anchoring devices are assembled and fixed in position while the refrigerator is under construction. One end of the anchor devices, the bolt head, extends within the cooling chamber, and when not utilized to support a carrier for brine tanks they will not interfere with the capacity of the cooling chamber when the use of ice is desired as the cooling agent. The bolts are rigidly and tightly secured to the casing wall and will, therefore, provide strong anchors which will not deform the lining when a heavy brine tank is supported by a carrier which is secured to the bolts, and the arrangement of the anchor devices is such that no air will pass through the openings in the lining.

The end 23 of the bolt head 22 is flat and is provided with a central threaded aperture 24 to receive the threaded shank of a screw 25. The carrier is preferably made of a plurality of metal straps 16, which are secured at their ends against the flat ends 23 of the bolts by the screws 25 and such straps are arranged to carry the brine tank 27. The

straps can be readily attached to the bolts and thus installation of the carrier requires a very short period of time.

In the modified form of anchoring device 5 shown in Fig. 3, I utilize internally threaded sleeves 30, having a flanged end 31 as the anchor element, instead of the bolts previously described. The sleeve extends into the openings in the lining 15 and the casing 10 wall 14 previously described, and the shank of a screw 32 extends through a washer 33 and is screwed into the interiorly threaded end of the sleeve to draw the flanged end 31 tightly against the lining 15. The washer 15 33 bridges the upper end of the opening in the casing wall and serves to maintain the sleeve 30 and the screw 32 in relative fixed relation. The carrier straps bear against the flanged end of the anchor elements 30 and 20 are secured thereto by the screws 34, the shanks of which are screwed into the threaded interior of the anchor element 30.

It will be seen that with both forms of anchoring devices, I provide an anchor element which is fixed to the refrigerator casing 25 and extends partially within the cooling chamber, so that a brine tank carrier can be readily affixed thereto. This construction saves time in installation of the brine tank, 30 and provides a rigid support which is connected so that the weight of the brine tank will not deform the cooling chamber lining.

Various changes can be made in the details 35 of construction described herein, without departing from the spirit of my invention and the scope of the appended claims.

What I claim is:

1. A supporting device for anchoring a

brine tank carrier within the cooling chamber in a refrigerator casing comprising an anchor element extending through an opening 40 in the wall of the refrigerator casing and the cooling chamber lining, said anchor element having a flanged end portion extending within the cooling chamber, means for securing the flanged end of said anchor element tightly against the inner face of the cooling chamber lining, said anchor element being supported solely by the refrigerator casing, and detachable means for securing said tank 50 carrier to the flanged end of said anchor element.

2. A supporting device for anchoring a brine tank carrier within the cooling chamber of a refrigerator comprising an anchor element extending through and entirely supported by a wall of the refrigerator casing, 55 said anchor having a flanged portion within the cooling chamber adjacent the lining thereof, and means co-operating with said flanged 60 portion for securing said tank carrier to the flanged portion of said anchor.

3. A supporting device for anchoring a brine tank carrier within the cooling chamber of a refrigerator comprising an anchor element extending through and entirely supported by a wall of the refrigerator casing, 65 said anchor having a flanged portion within the cooling chamber, means for rigidly securing said anchor element to said casing, and means co-operating with said flanged portion 70 for securing said tank carrier to the flanged end of said anchor.

In testimony whereof, I hereunto affix my signature.

WALTER H. WHITTIER.
